COAL DELIVERY TRUCK

Earl H. McAfee, Detroit, Mich.

Application April 6, 1934, Serial No. 719,317

2 Claims. (Cl. 298—24)

My invention relates to a coal delivery vehicle adapted for storing, transporting, and discharging coal.

It has been the general practice in the past 5 to provide coal transporting vehicles, such as coal trucks, with apparatus for shiftably inclining the coal container in order to discharge the coal therefrom. Such a provision not only raised the initial cost of the vehicle but it also 10 resulted in expenditures for the upkeep of the apparatus. There was also the ever present likelihood that this movable apparatus would get out of order and render the vehicle useless until repaired.

15 An important object of this invention is to provide a coal container or bin upon a vehicle which does not require tilting apparatus but instead is self operating to discharge the coal therefrom with equal, if not better, effectiveness.

20 A further object of this invention is to provide a coal transporting vehicle with a coal box fixedly secured thereto and provided with a bottom so constructed with inclined floor sections that the coal within the box can be completely emptied in measured quantities through 25 a plurality of discharge outlets in the walls of the coal box.

To accomplish the above objects, the coal 30 transporting receptacle is constructed in a novel manner. A number of discharge outlets are provided about the receptacle adjacent the bottom of its wall portions. The floor of the bin is provided with inclined sections extending upwardly and away from the openings in several 35 directions and form a general funnel arrangement which causes the coal to collect adjacent the outlet. The upper, topmost portions of the inclined sections join with one another and the wall of the receptacle to form a plurality of compartments or stalls whose capacity may be, if 40 desired, a standard measure of coal. Each stall is thus provided with a discharge outlet at the lowermost level of its inclined floors, and upon opening any one of the outlets, the coal is easily 45 and rapidly discharged to any place of deposit outside of the vehicle.

Other advantages and important features of 50 my construction will more fully appear from the following description, appended claims and accompanying drawing wherein:

Figure 1 is a top view of my coal receptacle and its mounting upon a vehicle frame,

55 Fig. 2 is a side elevation of my coal receptacle having portions cut away to show the interior construction,

Fig. 3 is a cross sectional view of the coal receptacle and the supporting frame of the vehicle,

Fig. 4 is a rear end view of the coal receptacle showing the closure operating mechanism, and 5

Fig. 5 is an elevated view of a vehicle showing the position of the coal receptacle supported thereon.

In the drawing reference 10 indicates a vehicle frame upon which cross supporting members 10 12 are provided at spaced intervals. These cross members, as shown in Figs. 2 and 5 support a coal receptacle or bin generally indicated at 14. This receptacle is of a rectangular shape and open at the top in order to permit coal to 15 be loaded thereinto.

A number of openings 16 are provided in the walls of the bin and are located adjacent the bottom of the bin forming discharge outlets for the coal therein. Closure members for these 20 openings are indicated at 18 and are mounted to slide vertically between the rails 20. Manually operating mechanism for raising these closure members to open the discharge outlets is shown at 22 and comprises a pivoted handle 25 connected through linkage with the closure members 18. The closure members 18 are normally in closed position due to their weight, but they can be retained in open position by any obvious method such as that indicated in 30 the drawing wherein a removable element 24 is adapted to be secured in an aperture 26 to support the handle 22 in raised position as shown in Fig. 4.

The floor of the coal bin 14 is constructed in 35 such a manner about the discharge outlets 16 as to cause the coal near each of these outlets to gravitate in the direction of these outlets and to run out of the bin when the closure members are opened. The floor of the bin is provided 40 with inclined sections 30 extending rearwardly away from the outlets 16 and in an upward direction. Co-extending with the inclined sections 30 are other inclined floor sections 32 which terminate at their lowermost portions adjacent 45 to the discharge outlets. Floor supporting members 34 of any desired construction may be used for supporting the floors in inclined position. In order to obtain the best results with the minimum amount of waste space utilized, it is best 50 to incline these floor sections at approximately 45°.

The inclined floor sections 30 and 32 join with one another at 36 in the interior of the coal bin as shown in Fig. 1. Rising above the com- 55

mon junctures 36 of these inclined floor sections are vertical partitions 38. The latter partitions in conjunction with the inclined floor sections divide the coal bin into a plurality of stalls or 5 pockets, and the capacity of these stalls may be pre-arranged to contain a standard measure of coal. In the embodiment in the drawing, the larger stalls or compartments represent a capacity of one ton while the smaller compartments 10 are adapted to hold a half a ton each. A laterally extending flange 40 may be provided along the top of the partitions 38 in order to aid in retaining the coal within the stalls.

The performance of the coal receptacle 14 is 15 readily apparent. Upon opening a closure member 18 for one of the stalls, the inclined floor sections of this stall will cause the coal therein to roll downwardly in the direction of the outlet and to be discharged therefrom. Coal chutes 20 may be provided to collect the coal as it is discharged from the outlet and convey the coal to any point of deposit. If more than a ton, or a half a ton, has been ordered, the coal chute 25 can be attached adjacent any one of the other outlets in order to receive another measure of coal. In the event that it is difficult to connect the chute from a point of deposit to one of these discharge outlets, the coal truck can be turned around or otherwise moved to enable the connection 30 to be made.

When delivery of a number of small coal orders is required, a vehicle embodying this invention may be used to fill these orders in 35 one run. The transporting vehicle, having been filled up to capacity, can make a stop at each of the places desiring coal and deliver the measure of coal desired at each of these places.

While one illustrative embodiment of the invention has been described in detail, it is not 40 my intention to limit the scope to that particular embodiment than otherwise by the terms of the appended claims.

What I claim is:

1. In a motor vehicle having a supporting 45 frame, a coal box mounted on said frame having side walls and end walls, certain of said side walls each provided with a gate controlled discharge outlet adjacent the bottom thereof but above said supporting frame, one end wall provided with a pair of gate controlled discharge 50 outlets adjacent the bottom thereof, the floor of

said coal box provided with a plurality of inclined sections extending upwardly and away from each of said outlets, one of said inclined sections extending upwardly and away from one of said side outlets meeting with another inclined section extending likewise from the other side outlet substantially on the longitudinal median line of said coal box, another inclined section extending upwardly and away from each of said side outlets meeting with another inclined 10 section extending likewise from one of said end outlets on a line transverse to said coal box, other inclined sections extending upwardly and away from said outlets to connect with adjacent walls of the coal box, all of said inclined 15 bottom sections joining with one another and the walls of the coal box at a common height equal to the height of the walls of the coal box, said inclined sections arranged together to provide a plurality of pockets in said coal box of 20 general funnel shape each adapted to cause the coal therein to completely flow out through an outlet.

2. A vehicle for transporting measured quantities of coal comprising, in combination, a 25 longitudinal frame, a rectangular coal box mounted above said frame and provided with side and end walls, each of said side walls provided with a discharge outlet adjacent its bottom edge above the level of the frame, one of said 30 end walls provided with a pair of discharge outlets adjacent its bottom edge above the level of said frame, the floor of said coal box being formed of a plurality of inclined sections each having their lower edges terminating adjacent 35 the discharge outlets so as to cause the coal in the box to gravitate toward the outlets, a vertical partition extending along the longitudinal median line of the coal box, a second vertical partition extending transversely to the coal box at 40 substantially one third the length of the coal box from the end wall having the pair of discharge outlets, said longitudinal and transverse partitions dividing the coal box into two relatively 45 large stalls each adapted to hold a ton of coal and into two relatively small stalls each adapted to hold a half a ton, each of said stalls communicating with one of said discharge outlets to deliver coal therethrough.

50
EARL H. McAFFEE.
